(57) **CLAIM**

I claim the ornamental design for a headphone assembly, as shown and described.

DESCRIPTION

FIG. 1 is a top view of a headphone assembly in accordance with the new design, depicting two earpieces connected by a flexible cord.

FIG. 2 is a bottom view thereof, depicting two earpieces connected by a flexible cord.

FIG. 3 is a left side elevational view thereof, the cord is drawn broken away for purposes of illustration;

FIG. 4 is a right side elevational view thereof;

FIG. 5 is a left back elevational view thereof;

FIG. 6 is a right back elevational view thereof;

FIG. 7 is an opposite side left elevational view thereof;

FIG. 8 is an opposite right side elevational view thereof;

FIG. 9 is a left front elevational view thereof; and,

FIG. 10 is a right front elevational view thereof.

The dashed lines depict environmental aspects and form no part of the claimed design.
